DESIGN FOR REFRIGERATOR CABINET

Ralph E. Kruck, Springfield, Mass., assignor to
Westinghouse Electric and Manufacturing
Company, a corporation of Pennsylvania

Application August 9, 1932. Serial No. 44,567

Term of patent 3½ years

To all whom it may concern:

Be it known that I, RALPH E. KRUCK, a citizen of the United States, residing at Springfield, in the county of Hampden and State of Massachusetts, have invented a new, original, and ornamental Design for Refrigerator Cabinets, of which the following is a specification, reference being had to the accompanying drawing constituting a part hereof.

The single figure is an elevational perspective view of a refrigerator cabinet showing my new design.

I claim:—

The ornamental design for a refrigerator cabinet substantially as shown.

In testimony whereof, I have hereunto subscribed my name this 26th day of July, 1932.

RALPH E. KRUCK.
